[57] CLAIM

The ornamental design for a fluorescent lantern, substantially as shown and described.

DESCRIPTION

FIG. 1 is a perspective view of a fluorescent lantern showing my new design;

FIG. 2 is a right side elevational view thereof;

FIG. 3 is a top view thereof;

FIG. 4 is a left side elevational view thereof;

FIG. 5 is a bottom view thereof;

FIG. 6 is a front elevational view thereof; and

FIG. 7 is a rear elevational view thereof.

The fluorescent lamp and the incandescent lamp bulb are shown in broken lines for illustrative purposes only.
